UNITED STATES PATENT OFFICE.

RAY A. NORTH, OF GREEN BAY, WISCONSIN.

ATTACHMENT FOR BEATER-BARS.

1,185,926.

Specification of Letters Patent. Patented June 6, 1916.

Application filed February 20, 1915. Serial No. 9,711.

To all whom it may concern:

Be it known that I, RAY A. NORTH, a citizen of the United States of America, residing at Green Bay, in the county of Brown 5 and State of Wisconsin, have invented certain new and useful Improvements in Attachments for Beater-Bars, of which the following is a specification, reference being had therein to the accompanying drawing.

10 This invention relates to means for securing filling material between beating bars of an engine used in manufacturing paper, and has for its object the production of a simple and efficient means whereby the filling material may be readily removed from between the bars or replaced whenever it should become necessary to replace the worn filling material by new filling material.

Another object of this invention is the 20 production of a simple and efficient means for facilitating the replacing or removal of the filling material between the beating bars without changing or removing the beater bars.

25 Other objects and advantages of the present invention will appear throughout the following specification and claims.

In the accompanying drawings:—Figure 1 is a perspective view of a portion of two 30 beater bars. Fig. 2 is a vertical section through the securing means for holding the beater bars in an assembled position, and also holding the filling material between the beater bars. Fig. 3 is a detail perspective of one of the side plates of the beater bars. Fig. 4 is a perspective view of an embodiment of the present invention wherein three beater bars are employed. Fig. 5 is a transverse sectional view through a portion of the 40 beater bars showing the manner in which the filling material is securely held between the beater bars. Fig. 6 is a detail sectional perspective of a portion of one of the beater bars showing the sockets formed therein for 45 the purpose of receiving the retaining bolts. Fig. 7 is a detail perspective of one of the spacing sleeves used in connection with the present invention. Fig. 8 is a detail perspective of a portion of one of the sheets of fill- 50 ing material used in connection with the present invention.

By referring to the drawings it will be seen that 1 designates one of the beater bars which is secured to and held in spaced relation with the other beater bar 2 by means of a spacing bolt 3. It should be understood

that each of the beater bars 1 and 2 is provided with a notched portion 4, within which notched portion 4 fit the respective ends of the bolt 3. This structure is clearly illustrated in Fig. 1 of the drawings. A spacing sleeve 5 is placed upon the bolt 3 and is adapted to fit between the inner walls of the beater bars 1 and 2 and hold these beater bars in spaced relation.

Each beater bar is provided with a plurality of vertically extending notches 6 along the top edge thereof, which notches 6 terminate in enlarged concave pockets 7 for the purpose of receiving the conical heads 8 of the bolts 3, or the conical shaped nuts 9 of the bolts 3. It will, therefore, be seen that a very simple and efficient means has been produced for permitting the respective bolts 3 to be placed within the notches 4 and 6. Each bolt 3 carries a threaded nut 9 at one end, and each nut is provided with a plurality of sockets 10 for the purpose of receiving a suitable wrench to permit the operation of the nut 9 and allow the nut to be firmly threaded upon the threaded end of the bolt 3. This structure is clearly shown in Fig. 2 of the drawings.

A plurality of filler strips 11 are interposed between the beater bars 1 and 2, and these filler strips 11 are provided with notches 12 formed near each end thereof for the purpose of receiving the end bolts 3. These filler strips 11 are also provided with apertures 13 intermediate the ends for the purpose of permitting the intermediate bolts 3 to pass therethrough and firmly hold the filler strips 11 between the beater bars 1 and 2. A plurality of locking bolts 14 are secured to the beater bars 1 and 2 and are adapted to be threaded therethrough for the purpose of engaging the filler strips 11 and firmly hold these filler strips in binding engagement with each other.

Each beater bar 1 and 2 is provided with a band receiving notch 15 upon the edge thereof for the purpose of receiving a band of suitable construction, illustrated and described more thoroughly in Fig. 4, for holding the beater strips in engagement with the proper support.

Attention is now directed to Figs. 4 and 5 of the drawings wherein an embodiment of the invention is employed showing three spaced beater bars 16. These beater bars 16 are provided with the usual notches 17 and 18 similar to the notches 4 and 6 illustrated

in Fig. 1 of the drawings for the purpose of receiving the securing bolt 19 clearly illustrated in Fig. 3 of the drawings. This bolt 19 carries a plurality of sleeves 20 which are 5 adapted to hold the beater bars 16 in spaced relation. A plurality of filler strips 21 are interposed between the beater bars 16 and are firmly held in engagement with each other by means of the securing bolt 22 clearly 10 illustrated in Fig. 4 of the drawings. The bolt 19 is of similar construction to the bolt 3 and carries a threaded conical nut 22 at one end thereof for the purpose of fitting in the conical sockets formed in the inner ends 15 of the notches 17 and 18.

This construction is similar to that shown in Fig. 1, and these beater bars 16 are firmly held in engagement with a support 24 by means of a locking band 25, which locking 20 band fits in the notches 26 formed in the respective ends of the beater bars 16. It should be understood that the filler strips 21 fit upon the top face of the support 24.

It, of course, should be understood that any 25 suitable changes in the detail mechanical construction may be employed without departing from the spirit of the invention so long as these changes fall within the scope of the appended claims.

30 It also should be understood that these beater bars may be multiplied to any extent desired, and two, three, four, five, six, or even as high as an indefinite number may be employed without departing from the spirit 35 of the invention.

Having thus described the invention what is claimed as new, is:—

1. In a device of the class described the combination with a support, of a plurality 40 of beater bars, each beater bar provided with a plurality of notches formed therein, each notch terminating in a conical socket at its inner end, a plurality of connecting bolts fitting within said conical sockets and provided with means for snugly engaging said 45 conical sockets, means carried by said bolts for holding said beater bars in spaced relation, a plurality of filler strips interposed between said beater bars and provided with 50 means for receiving said bolts whereby said strips will be held in detachable engagement with said beater bars, and binding means carried by said beater bars for binding said filler strips together.

55 2. In a device of the class described the combination with a support, of a plurality of beater bars, each beater bar provided with a plurality of notches formed therein, each notch terminating in a conical socket at its inner end, a plurality of connecting bolts fitting within said conical sockets and provided with means for snugly engaging said

conical sockets, means carried by said bolts for holding said beater bars in spaced relation, a plurality of filler strips interposed 65 between said beater bars and provided with means for receiving said bolts whereby said strips will be held in detachable engagement with said beater bars, an adjusting screw carried by one of said beater bars and passing therethrough and engaging said filler strips for firmly binding said filler strips together.

3. In a device of the class described the combination with a support, of a plurality 70 of beater bars carried thereby, each beater bar provided with a plurality of notches formed near the edge thereof, each notch terminating in a conical socket at its inner end, securing bolts passing through said beater bars, each bolt provided with a conical head fitting in one of said conical sockets, a detachable conical nut threaded upon the opposite end of each bolt and fitting within the diametrically opposite socket of the adjacent beater bar, a plurality of filler strips interposed between said beater bars, said bolts passing through said filler strips for detachably holding said filler strips in engagement with said bars, sleeves carried by 80 said bolts for holding said beater bars in spaced relation, and binding means carried by one of said beater bars and engaging said filler strips for binding said filler strips in engagement with each other.

4. In a device of the class described the combination with a support, of a plurality of beater bars, each beater bar provided with a longitudinally extending notch near each end thereof, each notch terminating in a 100 conical socket at its inner end, each beater bar also provided with a plurality of vertically extending notches along the top edge thereof terminating in conical sockets at the inner ends of said notches, filler strips positioned between said beater bars, said filler strips provided with notches near each end thereof; a bolt positioned within the end notches of said beater bars and fitting within the end notches of said filler strips, said 105 filler strips provided with spaced apertures communicating with said vertically extending notches, and bolts passing through said vertically extending notches and through said spaced apertures for detachably holding said filler strips in engagement with said beater bars.

In testimony whereof I hereunto affix my signature in presence of two witnesses.

RAY A. NORTII.
